ASSIGNORS TO COLUMBIA GRAPHOPHONE MANUFACTURING COMPANY, OF
BRIDGEPORT, CONNECTICUT, A CORPORATION OF DELAWARE.

AUTOMATIC STOP.

Application filed April 8, 1918. Serial No. 227,281.

To all whom it may concern:

Be it known that we, FRANK C. HINCKLEY and JOHN J. SCULLY, citizens of the United States of America, and residents of Bridgeport, Connecticut, have invented a new and useful Improvement in Automatic Stops, which invention is fully set forth in the following specification.

This invention relates to stop mechanism, and particularly to stop mechanism especially designed for use in talking machines.

In machines of the latter type, a sound-box operatively connected to a sound-conveying member, which together will be referred to as a traveling element, has movement relatively to a rotary record-support, which support, or any other suitable motor-driven member, will be referred to hereafter as a rotating element, the sound-box and sound-conveying member generally being fed across the record-support by the coaction of the former with the groove in the sound-record tablet. It is an object of this invention to provide a stop mechanism of improved construction, which shall stop the rotation of the record-support or other rotating element upon the completion of the traverse of the sound-box and sound-conveying member.

30 A further object of this invention is to provide stop mechanism of the character referred to, with improved means whereby a predetermined number of revolutions of the rotating element must occur before said stop mechanism can come into action, whether the traveling element be stationary or not.

40 A still further object of the invention is to provide a stop mechanism of the type characterized with a manually-operable controlling member by which the machine may be stopped at any time independently of the mechanism for automatically stopping the same.

45 Yet another object of the invention is to provide a stop mechanism of the type characterized for use in connection with a motor hinged to its support, whereby the motor may be swung into and out of its normal position without the necessity of manually connecting and disconnecting the parts of the stop mechanism respectively connected to the movable motor and the stationary support.

Other objects relate to the provision of a stop mechanism of the type in question which is simple in construction, inexpensive to manufacture and install, and efficient in operation.

Stated broadly, the invention comprises, in combination, a rotating element, a traveling element, stop mechanism, a member for actuating the same shown as a rotating member, means operatively connected with the rotating element for moving said member into stop-actuating position, and means operatively connected with the traveling element for preventing the movement of said member into stop-actuating position while the traveling element continues its traverse, said stop mechanism being controlled by a member, shown as a detent, and preferably both pivotally and bodily movable, which coacts with said stop mechanism to move said controlling member out of operative relation with said actuating member upon actuation of said stop mechanism. Preferably a predetermined number of revolutions of the rotating element must occur before said actuating member comes into approximate stop-actuating position, said means operatively connected with the traveling element thereafter, and so long as the traveling element continues its traverse, preventing said actuating member from moving into final stop-actuating position. Said stop mechanism, which may be either a brake or a switch, is operatively connected with a manual controlling member for moving said stop mechanism into starting position, and a manually-operable member is also preferably provided for effecting the actuation of said stop mechanism independently of the automatic mechanism above referred to.

The invention is capable of receiving a variety of mechanical expressions, one of which is shown on the accompanying drawings, but it is to be expressly understood that the drawings are for purposes of illustration and are not to be construed as a definition of the limits of the invention, reference being had to the appended claims for that purpose.

In said drawings:—

Fig. 1 is an end view of a talking machine provided with automatic stop mechanism in accordance with the present invention;

Fig. 2 is a plan view of the stop mech-

anism, showing the machine stopped but, for convenience, the stop-actuating member in the position it assumes during the normal operation of the machine;

5 Fig. 3 is a fragmentary plan, parts being omitted for the sake of clearness, showing the machine in operation and the stop-actuating member in an intermediate position;

10 Fig. 4 is a detail perspective of the brake lever and its controlling member;

Fig. 5 is a fragmentary detail perspective of the motor-drive of the actuating member; and

15 Fig. 6 is a perspective view of the manually-operable stop-actuating member.

Referring in detail to said drawings, wherein the same reference characters designate corresponding parts in the several figures, 1 represents the driving spindle of a rotary record-support 2 designed to carry the usual record-tablet, and 3 the usual sound-box connected to the tone-arm 4 suitably mounted on the talking machine casing 20 as by a bracket 5, said tone-arm being mounted in any suitable way to enable the sound-box to traverse a record on said support.

Frictionally connected to the tone-arm in 30 any suitable way is an arm 6 provided at its outer end with an operating nose 7 engaging in the slot provided by the bifurcated end 8 of a lever 9 pivotally mounted at 10 on the motor-board 11. The opposite 35 end of said lever 9 is provided with an operating nose 12 for a purpose to be explained hereinafter. To limit the movement of said lever, a pair of adjustable stops 13 may be threaded into lugs 14 carried by the motor-frame 15.

Rotatably mounted on the motor-frame at 16 is an actuating member 17 shown as a gear provided with a plurality of radial teeth 18. Carried by said member 17 is a 45 pair of lugs 18^a and 19, one or both of which are designed to coact with the operating nose 12 of the lever 9 and with a controlling member to be described. Suitable means are provided for positively and intermittently 50 rotating the member 17 from the motor of the machine. In the form shown, a pinion 20, meshing with a gear 21 in the drive of the spindle 1, is carried by a stub shaft 22 upon which is mounted a rotary pawl 23 55 shown as provided with a single tooth designed to engage the teeth 18 of the member 17 and rotate the latter through a distance equal to the pitch of the teeth.

Pivotally mounted on the motor-frame at 60 24 is a brake lever 25 provided with an operating arm 26 and, in the form shown, with a depending arm 27 carrying a brake element 28 designed to engage the usual brake disk of the talking machine governor. It 65 is to be expressly understood, however, that

the invention is not limited to the use of a brake pad, as a switch might be operated by said lever 25, nor to the application of the brake pad to the governor disk, as by suitable variation said brake pad might engage other rotary members driven from the motor. The inner end of lever 25 is provided with a nose 29 for coaction with a controlling member to be presently described, said lever being normally drawn 70 into operative relation with said controlling member by a spring 30 connected at one end to lever 25 and at its opposite end to a pin 31 suitably provided on the motor-frame.

Pivoted on a pin 32 carried by the motor-frame is a controlling member 33 which, in the embodiment of the invention illustrated, performs the function of a detent for the brake lever 25. Said detent 33 is also mounted on the pin 32 for vertical bodily movement longitudinally of said pin. Detent member 33, which may be desirably made by bending the same up from a form struck out of sheet-metal, is provided with 80 an operating nose 34 designed to coact with one or both of the lugs 18^a and 19 projecting upwardly from the member 17, with an ear 35 designed to coact with the brake lever 25 and maintain the same in inoperative 90 position, and with a cam surface 36 shown as an arm bent upwardly, then inclined downwardly and forwardly, and then inclined again upwardly to a point slightly in advance of the ear 35. A spring 37 suitably connected at one end to the detent member 33 and at its opposite end to a pin 38 carried by the motor-frame, normally retains 95 said member in its lowermost position and in engagement with an adjustable stop 39 threaded into a lug 40 provided on the motor-frame, said spring, however, permitting both pivotal and vertical bodily movement of said member.

For starting the machine, a starting lever 41 is pivotally mounted on the motor-board 11 at 42 and provided with an operating nose 43 designed to engage the arm 26 of the brake lever 25. A spring 44, suitably connected to the starting lever 41 at one 110 end and to a pin 45 at its opposite end, normally maintains said starting lever at the end of its limiting slot in the position shown in Fig. 2.

Means are also preferably provided to enable the manual actuation of the stop mechanism independently of the means for securing an automatic actuation thereof. To this end, a spring-controlled stopping lever 46 is shown pivoted to the motor-board 115 at 47, said lever being provided at one end with a finger-piece 48 projecting through a slot in the motor-board and at its opposite end with an operating nose 49 designed to engage and rotate the detent member 33. 120

In the form of the invention shown, the motor is mounted for movement into and out of its normal position about a hinge 50 as shown in Fig. 2. Owing to the relation of 5 the end 7 of arm 6 and the bifurcated end 8 of lever 9, said lever may move with the motor into and out of operative engagement with said arm without requiring manual connection or disconnection of the parts constituting the train of mechanism between 10 the tone-arm and the stop-actuating member 17.

To start the machine, lever 41 is swung from the position shown in Fig. 2 to the 15 position shown in Fig. 3 against the tension of spring 44. During this movement, operating nose 43 engages arm 26 of lever 25 and moves said lever against the tension of spring 30 until nose 29 on said lever is 20 moved out to a position wherein spring 37 may snap ear 35 on member 33 behind said nose 29 to retain the stop lever in off position, as shown in Fig. 3. As nose 29 is moved outwardly, the detent member 33 is 25 also drawn downwardly by the spring 37 as fast as is permitted by the coaction of the inclined end of arm 36 with said nose 29.

Brake element 28 being now withdrawn from engagement with the governor disk, the 30 motor starts and rotates the spindle 1 and record-support 2. Gear 21 rotates gear 20 and, through shaft 22, the rotary pawl 23. At each rotation, said pawl engages one of the teeth of the stop-actuating member 17 35 and advances the same through a distance equal to the pitch of the teeth. In order to advance the lugs 18 and 19 on said member 17 from their position when the machine is stopped into operative relationship with nose 12 of lever 9 and nose 34 of detent 33, the member 17 must make half a revolution. While said member is making this one-half revolution, ample time is provided for the 40 positioning of the sound-box in operative relation in the outer groove of the record-tablet. Thus, assuming that there are twenty teeth on the member 17 and that gear 20 makes one revolution for each seven and a half revolutions of the turn-table spindle, it 45 will require seventy-five revolutions of the turn-table before the lugs on member 17 are advanced into operative relationship with lever 9 and detent 33. It is to be expressly understood, however, that the invention is 50 not restricted to the use of twenty teeth on the member 17 nor to the lapse of one-half a revolution of said member before it assumes operating relationship with the lever 9 and detent 33, as any suitable number of 55 teeth may be employed on said member and, by suitable variation, the lapse of time before said member assumes operative relationship with the lever and detent may be less than one-half a revolution or as much 60 as a whole revolution.

The sound-box having been operatively engaged with the sound-record tablet during the period when member 17 is making a half revolution, the sound-box and tone-arm now traverse the record and, through the frictional connection between the tone-arm and the arm 6, tend to drive said arm in a clockwise direction. Operating nose 7 on said arm 6 by engagement with the bifurcated end 8 of lever 9 tends to drive said lever in 65 anti-clockwise direction. The extent of movement of said arm and lever is, however, limited by the engagement of said lever with one of the stops 13. Thereafter, until member 17 has been advanced in clockwise direction through one-half a revolution to approximately stop-actuating position, the arm 6 will slip with respect to the tone-arm 4. When one of said lugs 18 or 19 is advanced 70 into approximately stop-actuating position, it engages the operating nose 12 of lever 9 and moves said lever in a clockwise direction, said lever moving arm 6 in an anti-clockwise direction, which movement is permitted by the frictional connection between said arm 75 and the tone-arm. After pawl 23 moves out of engagement with said member 17, and while it is making its rotation to engage the next tooth of said member, arm 6 driven by the tone-arm moves lever 9 in an anti-clockwise direction and, through its engagement with the lug on member 17, rotates the latter in a clockwise direction a distance equal to the pitch of the teeth. Pawl 23 then coming into engagement with the tooth on said 80 member moves the latter in an anti-clockwise direction an equal distance. Thereafter, and so long as the traveling element continues its traverse, member 17 is subjected to the intermittently and oppositely 85 acting impulses of the lever 9 and the pawl 23, whereby it oscillates in opposite directions through a limited arc. Throughout this period the other of the two lugs 18 and 19 on the member 17 is in approximately 90 stop-actuating position just out of engagement with nose 34 of detent 33. When the tone-arm ceases its traverse, lever 9 is no longer moved in an anti-clockwise direction to move member 17 in a clockwise direction. Said member therefore remains in the position to which it has been moved by the pawl 23, whereupon at the next engagement of pawl 23 with member 17, said member is 95 advanced in an anti-clockwise direction 100 through a further distance to engage the lug thereon with nose 34 of detent 33 and swing the latter about its pivot 31 against the tension of spring 37. Thereby ear 35 is drawn from engagement with nose 29 of lever 25 105 and said lever is drawn by the spring 30 along the cam face of arm 36 until brake element 28 engages the governor disk. Owing to the coaction of nose 29 with the cam 110 or inclined surface of arm 36, detent 33 is 115 120 125 130

2
moved upwardly along its pivot pin 31 until nose 34 is freed from the lug or member 17 in engagement therewith, whereby said lug may pass by said nose. The controlling member 33 being thereby moved out of operative relation with the stop-actuating member, the latter is in position to make a half revolution upon again starting the machine and before the lugs on said member resume 10 operative relationship with the lever 9 and member 33.

If it is desired to stop the machine prior to the automatic actuation thereof, or in case the automatic mechanism should not 15 operate, the machine may be stopped by pressing inwardly on lever 46 until nose 49 engages detent 33 and moves the same about its pivot to release stop lever 25 in the manner just described.

20 While the embodiment illustrated on the drawings has been described with considerable particularity, it is to be expressly understood that the invention is not restricted thereto as the same is capable of receiving a 25 variety of mechanical expressions some of which will readily suggest themselves to those skilled in the art, while certain parts thereof are capable of use without other parts thereof. Reference is therefore to be 30 had to the claims hereto appended for a definition of the limits of the invention.

What is claimed is:—

1. In combination, a rotating element, a 35 traveling element, stop mechanism, a controlling device therefor comprising a pivotally and bodily movable member, a second member for actuating the controlling member, the pivotal and bodily movement of the member adapted to position it to be operatively related to the second member and to the stop mechanism, means operatively connected with the rotating element for advancing the second member into approximate stop-actuating position while the rotating element makes a predetermined number of revolutions, and means operatively connected with the traveling element for preventing the second member from actuating the controlling member while the traveling 40 element continues its traverse.

2. In combination, a rotating element, a traveling element, stop mechanism, a controlling device therefor comprising a pivotally and bodily movable member, a second 45 member for actuating the controlling member, means operatively connected with the traveling element for moving the second member in one direction, and means operatively connected with the rotating element 50 for moving the second member in the opposite direction, the second member becoming operatively related to the controlling member only after a predetermined number of revolutions of the rotating element.

65 3. In combination, a rotating element, a

traveling element, stop mechanism, a controlling member therefor, a second member for actuating the controlling member, the stop mechanism adapted to coact with the controlling member to move the same out of operative relation with the second member, means operatively connected with the rotating element for advancing the second member into approximate stop-actuating position while the rotating element makes a predetermined number of revolutions, and means operatively connected with the traveling element for preventing the second member from actuating the controlling member while the traveling element continues its 70 traverse.

4. In combination, a rotating element, a traveling element, stop mechanism, a controlling member therefor, a second member for actuating the controlling member, the stop mechanism adapted to coact with the controlling member to move the same out of operative relation with the second member, means operatively connected with the traveling element for moving the second member 80 in one direction, and means operatively connected with the rotating element for moving the second member in the opposite direction, the second member becoming operatively related to the controlling member only after a predetermined number of revolutions of the rotating element.

5. In combination, a rotating element, a traveling element, stop mechanism, a controlling device therefor comprising a pivotally and bodily movable member, a second member for actuating the controlling member, the pivotal and bodily movement of the member adapted to position it to be operatively related to the second member and to the stop mechanism, means operatively connected with the rotating element for advancing the second member into approximate stop-actuating position, and means operatively connected with the traveling element for thereafter preventing the second member from operatively engaging said controlling member while the traveling element continues its traverse.

6. In combination, a rotating element, a traveling element, stop mechanism, a controlling device therefor comprising a pivotally movable member also movable longitudinally on its pivotal axis, a second member for actuating the controlling member, means operatively connected with the rotating element for intermittently moving the second member in one direction, and means operatively connected with the traveling element for moving the second member in the opposite direction intermittently while the traveling element continues its traverse.

7. In combination, a rotating element, a traveling element, stop mechanism, a controlling member therefor, a second member

- for actuating the controlling member, the stop mechanism adapted to coact with the controlling member to move the same out of operative relation with the second member, 5 means operatively connected with the rotating element for advancing the second member into approximate stop-actuating position, and means operatively connected with the traveling element for thereafter preventing the second member from operatively 10 engaging the controlling member while the traveling element continues its traverse.
8. In combination, a rotating element, a traveling element, stop mechanism, a controlling member therefor, a second member for actuating the controlling member, the stop mechanism adapted to coact with the controlling member to move the same out of operative relation with the second member, 15 means operatively connected with the rotating element for intermittently moving the second member in one direction, and means operatively connected with the traveling element for moving the second member in the opposite direction intermittently while the traveling element continues its traverse.
9. In combination, a rotating element, a traveling element, stop mechanism, a controlling device therefor comprising a pivotally movable member also movable longitudinally on its pivotal axis, a second member for actuating the controlling member, and means operatively connected with the rotating and traveling elements for operatively engaging the second member with the controlling member upon the stopping of the traveling element.
10. In combination, a rotating element, a traveling element, stop mechanism, a controlling member therefor, a second member for actuating the controlling member, the stop mechanism adapted to coact with the controlling member to move the same out of operative relation with the second member, 40 and means operatively connected with the rotating and traveling elements for operatively engaging the second member with the controlling member upon the stopping of the traveling element.
11. In combination, a rotating element, a traveling element, stop mechanism, a detent for the stop mechanism comprising a pivotally movable member also movable longitudinally on its pivotal axis, and means 45 operatively connected with the rotating and traveling elements for actuating the detent to release the stop mechanism upon the stopping of the traveling element.
12. In combination, a rotating element, a traveling element, stop mechanism, a detent for the stop mechanism comprising a movable member, and means operatively connected with the rotating and traveling elements for actuating the detent to release 50 the stop mechanism upon the stopping of the traveling element.
- the traveling element, the stop mechanism coacting with the movable member to move the same out of operative relation with the last-named means.
13. In combination, a rotating element, a traveling element, stop mechanism, a manually-operable member for moving the stop mechanism into starting position, means operatively connected with the rotating and traveling elements for actuating the stop mechanism upon the stopping of the traveling element, and a manually-operable member co-operating with said means for actuating stop mechanism. 70
14. In combination, a rotating element, a traveling element, stop mechanism, a detent therefor, means operatively connected with the rotating and traveling elements for actuating the detent to release the stop mechanism upon the stopping of the traveling element, and manually-operable means for actuating the detent to release the stop mechanism. 80
15. In combination, a rotating element, a traveling element, stop mechanism, a controlling member therefor, a second member for actuating the controlling member, means operatively connected with the rotating and traveling elements for moving the second member into operative engagement with the controlling member upon the stopping of the traveling element, and a manually-operable member for actuating the controlling member, the stop mechanism coacting with the controlling member to move the same out of operative relation with the second member when the controlling member is actuated by either of the actuating members. 90
16. In combination, a rotating element, a traveling element, stop mechanism, a controlling device therefor comprising a pivotally and bodily movable member, a rotatable member for actuating the controlling member, means operatively connected with the rotating element for intermittently moving the rotatable member in one direction, and means operatively connected with the traveling element for intermittently moving the rotatable member in the opposite direction while the traveling element continues its traverse. 105
17. A construction, as defined in claim 1, in combination with a manually operable means, co-acting with the pivotally and bodily movable member for actuating the stop mechanism at will, independently of the automatic actuation thereof. 120
18. A construction, as defined in claim 3, in combination with a manually operable means co-acting with the controlling member for actuating the stop mechanism at will, independently of the automatic actuation thereof. 125
19. A construction, as defined in claim 11, in combination with a manually operable means for actuating the stop mechanism upon the stopping of the traveling element. 130

member co-acting with the detent for actuating the stop mechanism at will, independently of the automatic actuation thereof.

20. In combination with a rotating element and a traveling element, stop mechanism, including a traveling member, a brake member, a connection between the traveling and brake members, including a rotatable member, and a detent, the detent being movable both pivotally about an axis and transversely to the plane of the rotatable member.

21. In combination with a rotating element and a traveling element, stop mechanism, including a traveling member, a brake member, a connection between the traveling and brake members, including a rotatable member, and a detent, the detent being movable both pivotally and transversely of the pivotal axis out of engagement with the rotatable member.

22. In combination, a rotating element, a traveling element, stop mechanism, a rotary member, a pair of diametrically-opposite and equally-spaced actuating lugs carried by the rotary member, one of said lugs adapted to cooperate with the stop mechanism to actuate it, means operatively connected with the rotating element for advancing said actuating member into approximate stop-actuating position, while the rotating element makes a predetermined number of revolutions, and means operatively connected with the traveling element adapted to cooperate with the other of said lugs for preventing said actuating member from moving into final stop-actuating position while the traveling element continues its traverse.

23. In combination, a rotating element, a

traveling element, stop mechanism, a rotary member, a pair of like diametrically-opposite and equally-spaced actuating lugs carried by the rotary member, one of said lugs adapted to cooperate with the stop mechanism to actuate it, means operatively connected with the rotating element for advancing said actuating member into approximate stop-actuating position while the rotating element makes a predetermined number of revolutions, and means operatively connected with the traveling element adapted to cooperate with the other of said lugs for preventing said actuating member from moving into final stop-actuating position, while the traveling element continues its traverse.

24. In combination, a rotating element, a traveling element, stop mechanism, a rotary member, a plurality of spaced lugs struck from the rotary member and formed integral therewith, one of said lugs adapted to cooperate with the stop mechanism to actuate it, means operatively connected with the rotating element for advancing said actuating member into approximate stop-actuating position while the rotating element makes a predetermined number of revolutions, and means operatively connected with the traveling element adapted to cooperate with the other of said lugs for preventing said actuating member from moving into final stop-actuating position while the traveling element continues its traverse.

In testimony whereof we have signed this specification.

FRANK C. HINCKLEY.
JOHN J. SCULLY.
